ATTORNEY

UNITED STATES PATENT OFFICE.

WILLIAM A. WILLIAMSON, OF NEWARK, NEW JERSEY.

DESIGN FOR A CAP-LIFT.

SPECIFICATION forming part of Design No. 29,798, dated December 13, 1898.

Application filed October 25, 1898. Serial No. 694,557. Term of patent 14 years.

To all whom it may concern:

Be it known that I, WILLIAM A. WILLIAMSON, a citizen of the United States, residing at Newark, in the county of Essex and State 5 of New Jersey, have invented and produced a new and original Design for a Cap-Lift; and I do hereby declare the following to be a full, clear, and exact description of the invention, such as will enable others skilled in 10 the art to which it appertains to make and use the same, reference being had to the accompanying drawings, and to letters of reference marked thereon, which form a part of this specification.

15 This invention is a new, original, and useful design for a device for detaching metallic, rubber, and other seals or caps from bottles; and the design consists, essentially, of the several features to be hereinafter described 20 and claimed, all of which will be fully understood by reference to the accompanying drawings, in which is illustrated an embodiment thereof.

In the drawings, Figure 1 is a perspective 25 view of the cap-lift embodying the leading features of my design. Fig. 2 is an end view, and Fig. 3 is a side view, of the same. Fig. 4 is a top or plan view of the cap-lift, and Fig. 5 is another perspective view of the same.

30 Similar letters of reference are employed in all of the above-described views to indicate corresponding parts.

As shown in the drawings, the leading or material feature of my design consists in the 35 cylindrical body a of the cap-lift, provided with a hole a' , extending centrally through said body a from the flat top or side a^2 to the

flat bottom or side a^3 . Extending from side to side of the cylindrical body a is a hole a^4 , arranged at right angles to the central hole 40 a' , as indicated in dotted outline in Fig. 4.

On one side of the cylindrical body a the side thereof has an outwardly-extending and downwardly-curved part a^5 , terminating at the bottom in a part a^6 , which has an angular 45 configuration formed by the curved part a^7 and straight edge a^8 , as will be clearly seen from an inspection, Figs. 2 and 4. Extending from the opposite cylindrical side of the body a are an outwardly and laterally projecting 50 curved surface a^9 and angularly-arranged sides a^{10} , the latter meeting to form a curved or circular and sharp edge a^{11} .

It will thus be seen that the leading features of my design reside in a cylindrical and 55 perforated body a and a pair of curved horns extending diametrically on opposite sides of said body, the one horn projecting in a downward direction approximately parallel with the longitudinal central axis of the said body 60 a and the other horn projecting laterally in a direction approximately at a right angle to the said longitudinal central axis of said body a .

What I claim is—

The design for a cap-lift, substantially as 65 herein shown and described.

In testimony that I claim the invention set forth above I have hereunto set my hand this 22d day of October, 1898.

WILLIAM A. WILLIAMSON.
